Primary Examiner—Celia Murphy*Attorney, Agent, or Firm*—Frank G. Morkunas[57] CLAIM

I claim the ornamental design for the surface ornamentation for garments, as shown and described.

DESCRIPTION

FIG. 1 is a top plan view of surface ornamentation for garments showing my new design;

FIG. 2 is a reduced perspective view thereof shown in use on a garment; and,

FIG. 3 is a reduced perspective view thereof shown in use on and alternate garment.

The broken lines showing a partial garment in FIG. 1 and the broken lines showing a shirt and pants for FIGS. 2 and 3, respectively, are for illustration purposes and form no part of the claimed design.
